HENRY R. HOWE, OF HARTWICK, NEW YORK.

Letters Patent No. 86,673, dated February 9, 1869.

IMPROVED CAR-COUPING.

The Schedule referred to in these Letters Patent and making part of the same.

To all whom it may concern:

Be it known that I, HENRY R. HOWE, of the town of Hartwick, in the county of Otsego, and State of New York, have invented a new and improved Car-Coupling; and I do hereby declare that the following is a full and exact description thereof, reference being had to the accompanying drawings, making a part of this specification, in which—

Figure 1 is a perspective view.

Figure 2, a longitudinal section through the centre, showing the internal arrangements of those parts which are not seen on the outside.

A is the buffer, constructed with a flaring mouth, to receive the link when the cars are brought together.

B is the platform or end of the car.

E is a block, constructed to operate in a suitable hollow cavity inside the buffer. It has a slot or mortise cut in it, through which a pin is inserted, to keep it in position, and allow it to operate the required distance.

G is a coiled spring, or its equivalent, in the cavity of the buffer behind block E, to operate said block.

C is the link by which the cars are connected.

D is the pin, which passes through the link, to connect it to the car. Said pin can be made of any shape desired.

H is a socket, to hold the pin D in position when it is raised out of the link.

N is a tongue in the mouth of the buffer. It has a small block, or its equivalent, in the centre of the front end, which rises inside the link, to prevent said link from turning laterally out of position, when not attached to both cars. Said tongue is constructed and arranged to guide and operate the link while the cars are being coupled together.

I I are arms, connected to the tongue, by which it is operated.

L is a jointed lever, of any suitable construction, which extends across the width of the car, so that it can be used from either side of said car. Said lever operates the pin D and the tongue N. It is so constructed, that, when the pin D is raised out of the link, the ends or handles of said lever will rest down in the desired position.

K K are arms, in front of the platform, with the end turned up, forming, in connection with the sliding jaws

O O, a receptacle to support and hold the lever L in position.

P P are chains, or their equivalents, which connect the arms I I and sliding jaws O O.

R R are braces, which support the arms K K.

S is a rod or pin, with a socket-head, by which pin D and lever L are connected.

Rod S and arms K K have coiled springs upon them, or their equivalents, to force forward the lever L to its right position, after being drawn back to raise and guide the link.

To operate this invention, raise up the pin D by the lever L, sufficiently high to permit the block E to come under the said pin, which uncouples the cars, and leaves the pin in the correct position for coupling. Put down the lever into its receptacle on arm K, where it will remain until it is needed to be used in recoupling.

To couple the cars, draw back the lever on the buffer that has the link in it, which forces back the jaw O, draws back the arm I, by the chain P, and thereby raises the tongue and link, and thus with the lever you guide the link into the mouth of the buffer on the car to be attached, and the end of said link strikes against the end of block E, forces it back, and permits the pin D to drop into the link, and the cars are coupled; and it can be done from either side of the cars without going between them.

I do not claim the whole of this coupling to be new and independent of that for which Letters Patent of the United States were granted unto me, on the 28th day of July, 1868, but rather an improvement on that contained in the aforesaid patent, dispensing with the large, heavy springs under the buffer, while the block E and spring G, in the cavity of the buffer, are the same, and the tongue nearly the same as in my former patent; therefore,

What I claim as my invention, and desire to secure by Letters Patent, is—

The construction and combination of lever L, rod S, pin D, socket H, arms I and K, and chain P, or their equivalents, connected with block E, spring G, tongue N, link C, and buffer A, arranged as described and set forth, for the purpose specified.
